UNITED STATES PATENT OFFICE.

CHESTER H. THORDARSON, OF CHICAGO, ILLINOIS.

COIL STRUCTURE FOR TRANSFORMERS AND THE LIKE.

1,326,223.

Specification of Letters Patent.

Patented Dec. 30, 1919.

Original application filed November 6, 1916, Serial No. 129,779. Divided and this application filed January 6, 1919. Serial No. 269,803.

To all whom it may concern:

Be it known that I, CHESTER H. THORDARSON, a citizen of the United States, residing in the city of Chicago, county of Cook 5 and State of Illinois, have invented certain new and useful Improvements in Coil Structures for Transformers and the like; and I do hereby declare that the following is a clear, full, and exact description thereof, 10 reference being had to the accompanying drawings and to the reference-numerals marked thereon and which form a part of this specification.

This invention relates to improvements in 15 windings for magnetic apparatus or devices and the improvements are herein shown as adapted to electrical transformers. However, the improved winding herein shown may be used in other magnetic machines or 20 apparatus.

Among the purposes of the invention is to provide a novel form of winding so constructed and arranged as to structurally strengthen the winding.

25 Another object of the invention is to provide an improved constricting band which surrounds or encircles the winding to hold the turns of the winding in place, and also serves as one end of the winding or coil to 30 which is attached a circuit wire.

A further object of the invention is to provide an encircling band of this character so constructed as to avoid corona discharge at the edges of the encircling band and 35 across the coil.

Another object of the invention is to provide means for supporting the inner turns of the conductors forming the winding or coil, constructed with means to force the 40 supporting member outwardly against the inner turns of the coil.

Other objects of the invention are to simplify and improve windings of the character described, and further to adapt such 45 windings to high tension transformers, and the invention consists in the combination and arrangement of the parts shown in the drawings and described in the specification, and as pointed out in the appended claims.

50 The present invention is shown as applied to that type of transformer illustrated in my prior application for U. S. Letters Patent, Serial No. 129,779, filed November 6, 1916, of which the present application is a division.

55 As shown in the drawings, Figure 1 is a

side elevation of a transformer embracing a winding or coil embodying my invention.

Fig. 2 is a section on the line 2—2 of Fig. 1.

Fig. 3 is a plan view showing a detail of 60 the high tension winding protecting ring or strip.

Fig. 4 is a section on the line 4—4 of Fig. 3.

Figs. 5 and 6 are details of an expanding 65 ring for supporting the inner turns of the high tension coil or winding.

As shown in the drawings, the core or magnetic structure embraces upper and lower yokes 10 and 11, respectively, and upright side members 12 and 13, all of laminated construction following the usual practice. 14 designates the low tension winding of the transformer and 15 designates as a whole the high tension winding. The core 75 or magnetic circuit and the particular relation of the high and low tension windings may follow any preferred or well known practice and constitutes no part of the present invention, the detail construction, however, being embraced and claimed in my said co-pending application, Serial No. 129,779. 80

The high tension coil 15 is of ring-like disk form and is preferably wound with a plurality of turns of insulated flat wire, the 85 several turns of which are insulated from each other. The said coil is insulated from the upper yoke 10 by an suitable insulating sleeve 16. It is interiorly supported by an open expandable ring 17 which is in electrical contact with the inner turn or end of the coil, and said ring is expanded against the interior of the coil by means of a wedge 18 made of insulating material. Said wedge is formed with edge grooves 18', as best 90 shown in Figs. 5 and 6 which engage the adjacent end edges of the expandable ring 17. Said end edges of the ring and the bottoms of the groove are tapered so that when the wedge is driven inwardly between the ends 100 of the band supporting ring the ring is expanded outwardly closely against the interior of the coil. It will be understood that said inner supporting expandable ring is electrically connected with the inner end 105 or turn of the coil or winding.

The said high tension coil 15 is supported and protected at its periphery by a flat metal band 20, which is formed to almost entirely encircle the coil and is clamped together at 110

its ends to effect a confining pressure on the coil. The side edges of said band or plates 20 are folded inwardly over the marginal portions thereof and preferably in close reinforcing wires 21, the effect of which rolled over edges is to eliminate corona discharge, and which in turn reduces liability of flashing over surfaces of the coil. The said wires 21, when employed, also serve to relieve the band or ring 20 from tension stress imposed thereon by drawing the ends of the band toward each other, as will hereinafter be described.

As herein shown, and preferably, the reinforcing wires 21 are made of a single length of wire bent in general U-shaped formation. The free ends of the wire at one end of the plate extend through openings in a terminal block 22 and are riveted thereto at 23. At the other end of the band the transverse member 24 of the U-shaped reinforcing wire extends transversely across the plate and is engaged by a clamping member 25 which is fixed by screws 26 to the terminal block. The said clamping plate is so arranged as to effect a clamping pressure on the bail or closed portion of the reinforcing wires when the said screws 26 are tightened. As herein shown, the clamping plate may assume an angle to the adjacent face of the terminal block 22 before the parts are adjusted, and the clamping screws 26, when screwed home, serves to bring the clamping plate 26 parallel to said adjacent face to effect the clamping pressure against the closed or bail-like portion 24 of the reinforcing wire. The said closed portion of the reinforced wire may be insulated from the clamping plate 25, as by an insulating member 27, or the clamping plate itself may be made of insulating material. One of the terminals 28 of the high tension coil or winding is mounted on the block 22 and its connection with the outer end of the high tension coil is through the protecting or encircling band 20.

The inner end of the high tension coil is connected to a terminal 30, shown in Fig. 1, which is mounted on the end of a metal arm 31 which extends from the inner portion of the coil outwardly to one side thereof in a direction generally parallel to the axis of the coil, and is attached to the inner expandable supporting ring 17 in any suitable manner. The terminal arm 31 is extended through the coil to the other side thereof and is turned upwardly at 32 to form between the same and the terminal block 22 a spark gap of such width as to protect the winding or coil.

The construction and assembly of the winding or coil contributes greatly to the strength and durability of the winding, and the winding is capable of being exposed to the elements without danger of impairing

the same. The terminal supports for said winding are also arranged in an exceedingly simple and efficient manner, thereby eliminating high tension cables and high tension insulators at the transformer or other apparatus to which the coil is applied.

It is to be understood that the invention is capable of considerable variation within the spirit and scope of the invention and that the foregoing description of the details showing one embodiment of the invention is not intended to be limiting, but it is the intent to claim all of inherent novelty shown in the drawings and described in the specification.

I claim as my invention,

1. A ring-like winding, an open expandable ring within and supporting the inner turns of said winding, and means acting on said ring to expand it outwardly against the winding.

2. A ring-like winding, an open expandable ring within and supporting the inner turns of said winding, and provided with oppositely inclined end edges and a wedge adapted to be driven between said end edges to expand the ring outwardly.

3. A ring-like winding, an open expandable ring within and supporting the inner turns of said winding, and provided with oppositely inclined end edges and an elongated wedge provided with laterally and oppositely opening grooves, the bottoms of which are tapered to engage the inclined end edges of said ring.

4. A ring-like winding, an open flat coil supporting ring fitting within the winding, and means acting against the ends of said ring to expand the ring outwardly against said winding.

5. A ring-like winding, a terminal connected to the outer end of the winding, and a metal terminal bar extending transversely through said winding and electrically connected to the inner end of the winding and provided at one end with a terminal and formed to provide between its other end and the outer winding terminal a safety air gap.

6. A ring-like winding, an open expandable ring within and supporting the inner turns of said winding and electrically connected to the inner turns of the winding, means acting on the ring to expand it outwardly against the winding, an outer terminal for said winding and a metal bar extending transversely through and at both ends beyond the winding and attached to said expandable ring, said bar being provided at one end with a terminal and curved at its other end toward the outer winding terminal to form between it and said latter terminal a safety air gap.

7. A ring-like winding, provided with an inner terminal, an open flat metal protecting ring embracing and clamped on said

winding and electrically connected to the outer end of the winding and an outer winding terminal connected to said ring.

8. A ring-like winding provided with an inner terminal, an open flat metal protecting ring embracing and clamped on said winding and electrically connected to the outer end of the winding, and an outer winding terminal connected to said ring, said ring being rounded at its edges to prevent corona discharge.

9. A ring-like winding provided with an inner terminal, an open flat metal protecting ring embracing said winding, reinforcing wires rolled in the side edges of said ring, a terminal block to which said wires are attached at one end of the ring, and a clamp carried by said block to engage said wires at the other end of said ring.

10. A ring-like winding provided with an

inner terminal, an open flat metal protecting ring embracing said winding, a single piece U-shaped wire bent between its ends, with the parallel members rolled in the side edges of the ring, a terminal block to which the ends of the said wires are attached, and a clamping member carried by said block to engage over the closed portion of said U-shaped wire.

11. A ring-like winding, an open flat metal protecting ring encircling said winding, with means engaging its ends to clamp it tightly against the inclosed winding, the side edges of said ring being curved or rounded for the purpose set forth.

In witness whereof, I claim the foregoing as my invention, I hereunto append my signature at Chicago, Illinois, this 3rd day of January, 1919.

CHESTER H. THORDARSON.
